UNITED STATES PATENT OFFICE.

SEWELL T. HADDEN, OF NEW YORK, N. Y.

SEWER-TRAP.

SPECIFICATION forming part of Letters Patent No. 391,143, dated October 16, 1888.

Application filed June 12, 1888. Serial No. 276,861. (No model.)

To all whom it may concern:

Be it known that I, SEWELL T. HADDEN, of New York city, New York, have invented a new and Improved Sewer-Trap, of which the following is a specification.

5 This invention relates to a sewer-trap so constructed that the bad gases from the sewer are effectively excluded from the house, and so that the greater the amount of back-pressure the 10 more firmly will the valve be closed.

The invention consists in the various features of improvement, more fully pointed out in the claim.

In the accompanying drawings, Figure 1 is a 15 vertical central section of my improved sewer-trap. Fig. 2 is a horizontal section on line $x-x$, Fig. 1; and Fig. 3, a bottom view of the guard j .

The letter a represents the lower section, and 20 b the upper section, of a cylindrical vessel, such sections being connected by a central tubular glass cylinder, c . The parts a c b constitute the chamber of the trap. The lower section, a , receives, preferably about midway from its bottom, the inlet-pipe d , connecting with a sink, bath-tub, &c., and opposite such pipe there is a screw-plugged opening, e , for the removal of sediment that may settle in section a beneath the mouth of pipe d . Above pipe d the section a is provided with a flange, a' , upon which 25 is set an annular removable plate, f , provided with the flaring valve seat f' , upon which rests the solid-rubber ball-valve g . The lower edge of the glass cylinder c is set upon the annular 30 plate f , while the upper edge of such cylinder supports the upper section, b , by means of a flange, b' , projecting inwardly from said section. This section b connects at about its center with the outlet-pipe h , that leads to the 35 sewer. The upper side of section b has an opening, which is closed by a screw-plug, i , from which depends the stem of guard j , having 40 a cross-shaped form, as shown in Fig. 3. This guard projects beneath the mouth of pipe

h , and as the water-level in the trap is above 45 such guard—namely, the line m m —all hair or other matter that may float upward will be arrested by the guard.

In order to connect the parts a c b of the trap, the parts a b are provided with angle-plates k , 50 connected by bolts l and nuts n .

The operation of the device is as follows: Pressure from the inlet-pipe d will raise the valve g from its seat to permit the passage of the waste through the trap and into the sewer. 55 As soon as the pressure releases, the valve settles upon its seat. Sediments deposited in section a are from time to time removed through the screw-plugged opening e , while lighter or floating matter that is carried upward is arrested by the guard j . The operation of the trap may at all times be inspected through its central glass section, c .

If it should be necessary to subject the entire trap to a thorough cleaning, it may be 65 taken entirely apart by unscrewing nuts n .

India-rubber packing-rings v v are placed between the ends of the glass cylinder c and the flanges a' and b' to make a tight joint.

Even if all the water in the trap should 70 evaporate or should be siphoned out the ball-valve will close tightly upon its seat.

What I claim is—

The combination of section a with the laterally-entering inlet-pipe d , and with a screw-plugged opening opposite thereto, and with a flange in the upper part of section a and with a plate, f , having valve seat f' , supported upon said flange, and with a central section, c , supported upon plate f , and with an upper flanged 75 section, b , having laterally-entering exit-pipe, and with a screw-plug, i , in the top of section b , and with a guard, j , depending from such plug, substantially as specified.

SEWELL T. HADDEN.
